SPINNING FRAME

Walter S. Eastman, Glendale, R. I., assignor to
 Stillwater Worsted Mills, a corporation of
 Rhode Island

Application June 4, 1940, Serial No. 338,790

24 Claims. (Cl. 19—135)

My invention relates to spinning frames.

It has among its objects to provide an improved spinning frame, and, more particularly, one wherein it is made possible to produce materially stronger yarn. A further object of my invention is to provide such an improved mechanism wherein it is made possible to divorce the twist from the draft while maintaining the yarn under pressure in an improved manner enabling stronger yarn to be produced and reducing breakage of the same. A still further object of my invention is to provide such an improved pressure mechanism having improved yarn supporting and pressure means cooperating with any usual top front roll of the spinning frame in an improved manner while disposed in an improved position relative thereto and to the yarn and yarn guide. A still further object of my invention is to provide an improved pressure attachment including such an improved pressure means and adapted to be applied to a standard spinning frame with facility and at small expense in such manner as to enable my improved results to be obtained. These and other objects and advantages of my improvements will, however, herein-after more fully appear.

In the accompanying drawing, I have shown for purposes of illustration one embodiment which my invention may assume in practice.

In the drawing:

Figure 1 is a sectional end elevation of a portion of a spinning frame embodying my improvements;

Fig. 2 is a front elevation of the same;

Fig. 3 is a sectional view on line 3—3 of Figure 1, and

Fig. 4 is a perspective view showing my improved roll and its supporting bracket removed from the frame.

In this illustrative construction, I have shown a spinning frame including a usual carriage stand, generally indicated at 1, and carrying drafting mechanism including usual top and bottom back rolls 2 and 3, usual carrier rolls 4 operating upon the roving or yarn 5 before the latter passes between the usual front rolls, herein comprising the cork covered top front roll 6 and the lower fluted front roll 7, and from which rolls 6 and 7 the drafted and twisted yarn usually passes to whirled bobbins 8 under suitable caps 9; my improvements herein including improved pressure mechanism acting on the yarn after it has passed between the rolls 6 and 7 and before it passes to the bobbins 8.

Referring more particularly to my improved

construction, it will be noted that I provide a new cooperating roll 10 acting upon the yarn at a point in front of the nip of rolls 6 and 7 at a point substantially below the axis of the roll 6, one of these rolls 10 being provided for cooperation with each cork covered roll 6. Herein, a pair of rolls 10 cooperating with a pair of adjacent rolls 6 is connected together, the rolls 10 herein being formed on the ends of an elongated roll carrying member 11 having journal pins 12 projecting from its opposite ends. As shown, this member 11 with the rolls 10 on the opposite ends thereof is movable in upright slots 13 on the lower ends of bracket members 14, and the upper ends of these members 14 are suitably connected to the carriage stand horn 15 on opposite sides of adjacent rolls 6 and between the opposite sides of the latter and the next adjacent rolls 6. Further, it will be noted that springs 16 provide journals for the pins 12 and are connected between the latter and suitable connections 17 on the upper ends of the brackets 14, these springs acting to hold the rolls 10 on the member 11 normally in contact with the undersides of the cooperating cork covered top front rolls 6. While other material may be used if desired, herein the rolls 10 are formed of hard wood with a smooth surface, it being found that such material has a coefficient of friction sufficiently close to that of the cork rolls 6 to produce a satisfactory operating combination. Further, herein, for convenience both of these rolls 10 are provided in the form of cylindrical enlargements on the opposite end of an integral hard wood roll carrying member 11. Attention is also directed to the fact that the rolls 10 are so disposed that the yarn passes off from the top thereof at a point above the center of a closed pigtail 18 carried in a usual position on the frame spaced beneath the latter 40 and above the top of the cap 9.

In the operation of my improved construction, it will be noted that the rolls 6 and 7 continue to perform their drafting function. However, my improved rolls 10, one of which cooperates 45 with each pair of rolls 6 and 7, pass the drafted yarn into contact with the underside of the cork covered rolls 6 at points spaced in front of the nip of the rolls 6 and 7. As a result, after the completion of the drafting process, a short length 50 of yarn engaging the underside of the rolls 6 throughout its length and indicated at 5a, is provided between the nip of the rolls 6, 7, and the nip of the rolls 6, 10. Further, it will be noted that this length 5a is of drafted but untwisted yarn and that an extension thereof, indicated at

5aa, extends from the nip of the rolls 6, 10 over the rolls 10, the twisting process not beginning at a point on the roll 7 or, as usual, at the nip of the rolls 6, 7, but instead beginning, as shown in Fig. 3, where the yarn passes downward off of the curved yarn supporting surface provided by the tops of the pressure rolls 10 which are rotated by the rolls 6. Thus, a twisted section 5b of yarn, shorter than that usual heretofore, is provided in which the yarn is not twisted until it leaves my improved yarn pressing and supporting rolls 10, and from which the yarn then passes directly down (Figure 3) into the closed pigtail guide 18 in such manner that the twist beginning at the roll 10 causes this yarn section 5b to be rotated around and in uniform contact with the entire inner circumference of the pigtail 18, while the twist is a continuous twist extending clear down from the roll 10 to the bottom of the cap 9.

As a result of my improved construction, it is made possible to obtain a materially stronger yarn than that heretofore obtainable, the yarn in fact being approximately twenty per cent stronger. This is believed to be due to the divorcing of the drafting and twisting processes made possible by my improved yarn pressing and supporting rolls 10 whereby the shorter lengths of yarn 5aa, 5b are produced between the rolls 6 and the bobbins, and also to the improved twisting action and the new uniform pressure on the yarn made possible by the provision of the pressure rolls 10 cooperating with the top front rolls as above described. Yarn breakage is also reduced by this improved construction, which also makes possible an improved contact with the pigtail as well as the use of a large cap and obtaining a substantially larger doff than heretofore. The increased strength of the yarn also makes possible higher operating speeds and larger packages than possible heretofore, while due to the larger packages, it is also made possible to eliminate doubling. By having the pressure rolls cooperate with the relatively smooth top front rolls 6, rather than the fluted rolls 7, in addition to supporting the yarn while free from pressure and spacing the beginning of twisting and obtaining markedly more uniform pressure, my improved construction also makes it possible to eliminate excessive wear on the pressure rolls while also making it possible to utilize hard wood or metal pressure rolls without causing shearing of the yarn by the fluted rolls 7. These, and other advantages of my improvements will, however, be apparent to those skilled in the art.

While I have in this application specifically described one form which my invention may assume in practice, it will be understood that the same has been chosen for purposes of illustration and that the invention may be modified and embodied in other forms without departing from its spirit or the scope of the appended claims.

What I claim as new and desire to secure by Letters Patent is:

1. In a spinning frame, drafting mechanism including cooperating front rolls, and mechanism for divorcing the twisting function from the drafting function of said rolls including means for effecting twisting while maintaining the yarn under pressure and spacing the beginning of twisting from said pressure.

2. In a spinning frame, drafting mechanism including cooperating front rolls, and mechanism for divorcing the twisting function from the drafting function of said rolls including means

for effecting twisting while maintaining the yarn under substantially uniform pressure and supporting free from said pressure the portion of the yarn where twisting begins.

5. 3. In a spinning frame, drafting mechanism including cooperating front rolls, and mechanism for divorcing the twisting function from the drafting function of said rolls and for effecting subsequent twisting including yarn supporting means for maintaining the yarn under pressure and thereafter supporting the same free from pressure during twisting.

4. In a spinning frame, drafting mechanism including cooperating front rolls, and mechanism for divorcing the twisting function from the drafting function of said rolls and for effecting subsequent twisting including yarn supporting means for maintaining the yarn pressed against the top front roll during twisting and having a

20 portion out of contact with said roll supporting the yarn to be twisted, free from pressure during twisting.

5. In a spinning frame, drafting mechanism including cooperating front rolls, and mechanism for divorcing the twisting function from the drafting function of said rolls and for effecting subsequent twisting including pressure means pressing the yarn against the top front roll and supporting the yarn after it passes through said pressure means.

6. In a spinning frame, drafting mechanism including cooperating front rolls, and pressure mechanism including yarn supporting pressure means disposed in front of the nip of said front rolls and having a portion supporting the yarn after it is freed from the pressure of said pressure means, and means acting on said pressure means for pressing the yarn against the top front roll.

40 7. In a spinning frame, drafting mechanism including cooperating front rolls, and twisting mechanism including yarn supporting pressure means disposed in front of the nip of said front rolls and having a portion supporting the yarn after it is freed from the pressure of said pressure means, and means acting on said pressure means for pressing the yarn against the underside of the top front roll.

8. In a spinning frame, drafting mechanism 50 including cooperating front rolls, and pressure mechanism including a yarn supporting pressure roll in front of the nip of said front rolls and supporting the yarn after it is freed from the pressure of said pressure roll and means acting on said pressure roll for pressing the yarn against the top front roll.

9. In a spinning frame, drafting mechanism including cooperating front rolls, and pressure mechanism including a yarn supporting pressure roll spaced out of operative relation with the lower front roll in front of the nip of said front rolls and disposed under the top roll, and means acting on said pressure roll for pressing the yarn against the underside of said top front roll.

60 10. In a spinning frame, drafting mechanism including cooperating front rolls, pressure mechanism including a yarn supporting pressure member over which yarn passes in front of the nip of said front rolls, and means acting on said member for pressing the yarn against the top front roll, said yarn supporting pressure member maintaining the yarn pressed against the top roll and supporting the portion of the same to

be twisted, free from pressure while the yarn passes off of said pressure member.

11. In a spinning frame, drafting mechanism including cooperating front rolls and pressure mechanism including a pressure member in front of the nip of said front rolls, and means acting on said pressure member for pressing the yarn against the top front roll, said pressure member having a surface pressing the yarn against the surface of said top roll and a yarn supporting surface in front of said pressure surface and spacing the point where the yarn leaves said supporting surface from the point where the yarn is freed from pressure.

12. In a spinning frame, drafting mechanism including cooperating front rolls, and pressure mechanism including a yarn supporting pressure roll over which the yarn passes in front of the nip of said front rolls and means acting on said pressure roll for pressing the yarn against the top front roll at a laterally spaced point from the point where the yarn leaves said pressure roll, said top roll having a cork surface and said pressure roll having a surface having a coefficient of friction adapted to cooperate with said cork surface.

13. In a spinning frame, drafting mechanism including cooperating front rolls, and mechanism for divorcing twisting from the drafting function of said rolls including yarn supporting pressure means over which the yarn passes for pressing the yarn against the top front roll, and means out of contact with said top roll for supporting, free from pressure, the yarn to be twisted as it passes from said pressure means.

14. In a spinning frame, drafting mechanism including cooperating front rolls, mechanism for divorcing twisting from the drafting function of said rolls including yarn supporting means for maintaining the drafted yarn under pressure, means for supporting, free from pressure, the yarn to be twisted as it passes from said pressure means, and twisting mechanism including an annular guide having its center directly below the point where the yarn leaves said supporting means.

15. In a spinning frame, drafting mechanism including cooperating front rolls, and mechanism for divorcing twisting from said rolls including means for maintaining the drafted yarn under pressure, and yarn supporting means for laterally spacing the beginning of twisting from the pressed portion of the yarn while maintaining the portion to be twisted free from pressure.

16. In a spinning frame, drafting mechanism including cooperating front rolls, pressure mechanism including yarn supporting pressure means over which the yarn passes in front of the nip of said front rolls for pressing the yarn against the top front roll and for supporting, free from pressure, the yarn leaving said pressure means, and twisting mechanism including a closed circumferential guide having its center spaced directly below the point where the yarn leaves said pressure means.

17. In a spinning frame, drafting mechanism including cooperating front rolls, pressure mechanism including pressure means in front of the nip of said front rolls for pressing the yarn against the top front roll and having a yarn supporting portion over which the yarn passes downward off of said portion after being freed from said pressure, and twisting mechanism in-

cluding a closed circumferential guide having its center spaced directly below the point where the yarn leaves said portion.

18. In a spinning frame, drafting mechanism including cooperating adjacent pairs of front rolls, and pressure mechanism including yarn supporting pressure rolls over which the yarn passes in front of the nip of said front rolls for pressing the yarn against the top front rolls and having a roll carrying member carrying said pressure rolls at opposite ends thereof, and means acting on said member normally maintaining said pressure rolls in operative position.

19. In a spinning frame, drafting mechanism including cooperating adjacent pairs of front rolls, and pressure mechanism including yarn supporting pressure rolls over which the yarn passes in front of the nip of said front rolls for pressing the yarn against the top front rolls and having a roll carrying member carrying said pressure rolls at opposite ends thereof, and tensioning means acting on said member normally maintaining said pressure rolls in operative position.

20. In an attachment for spinning frames having front drafting rolls, pressure mechanism including yarn supporting pressure means over which the yarn passes for pressing the yarn against the top front drafting roll in front of the nip of said front rolls and for supporting, free from pressure, the yarn leaving said pressure means, and means for maintaining said yarn supporting pressure means pressed toward said top roll.

21. In an attachment for spinning frames having front drafting rolls, pressure mechanism including a pressure means for pressing the yarn against the top front drafting roll in front of the nip of said front rolls, and means for maintaining said pressure means pressed toward said top roll, said pressure means having a portion supporting the yarn and over which the latter passes downward after being freed from the pressure of said pressure means.

22. In an attachment for spinning frames having front drafting rolls, pressure mechanism including a yarn supporting pressure roll over which the yarn passes for pressing the yarn against the top front drafting roll in front of the nip of said front rolls and supporting, free from pressure, the yarn leaving said roll, and means for maintaining said yarn supporting pressure roll in operative relation with said top roll.

23. Mechanism for divorcing the twisting function from the drafting function of top and bottom front drafting rolls including means for maintaining under pressure an intermediate portion of the yarn leading away from said bottom roll, and means for supporting the portion of the yarn to be twisted while maintaining it free from pressure.

24. Mechanism for divorcing the twisting function from the drafting function of top and bottom front drafting rolls including means for maintaining an intermediate portion of the drafted yarn under pressure, means receiving the yarn from said pressure means for supporting the portion of the yarn to be twisted while maintaining it free from pressure, and means for twisting the yarn leaving said supporting means so that twisting begins where the yarn passes off of said supporting means.
